MECHANICAL STOKER

Milburn E. Yeager, Needham, Mass., assignor to
National Engineering & Mfg. Co., Inc., a cor-
poration of Rhode Island

Application February 11, 1939, Serial No. 255,851

6 Claims. (Cl. 110—36)

My present invention relates to a stoking apparatus, and more particularly to a combination stoker and rotating grate.

The principal object of the present invention 5 is to provide an apparatus for simply and efficiently feeding measured quantities of coal to a revolving grate of a furnace.

Another object of my invention is to provide a combination stoker and grate which will 10 distribute the fuel uniformly in the most economical manner for consumption on the grate and eliminate waste.

Another object of the present invention is to 15 provide a stoking apparatus and grate which will eliminate the accumulation of ash tending to clog the circulation of air and the fire draft.

Another object of the present invention is to 20 provide a combination stoker and grate having a novel type of draft distribution which will insure an even and economical burning of the fuel at 25 all points on the grate.

A further object of the present invention is to 25 provide an apparatus having the above advantages which is easy and economical to manufacture and assemble and which is composed of a plurality of readily replaceable parts.

With the above and other objects and other 30 advantageous features in view, my invention consists of a novel arrangement of parts more fully disclosed in the detailed description following, in conjunction with the accompanying drawings, and more specifically defined in the claims appended hereto.

In the drawings:

Fig. 1 is a top plan view, partly in section, of 35 my new combination stoker and grate;

Fig. 2 is a section taken along line 2—2 on Fig. 1;

Fig. 3 is a plan view of the grate, partly in section, showing the rotating mechanism;

Fig. 4 is a section taken along line 4—4 on Fig. 1;

Fig. 5 is a detailed sectional view of the feeding and rotating apparatus;

Fig. 6 is a section taken along line 6—6 on Fig. 1;

Fig. 7 is a section taken along line 7—7 on Fig. 2;

Fig. 8 is an enlarged perspective view of one 50 of the interlocking rim sections;

Fig. 9 is an enlarged perspective view of the other interlocking rim section.

Fig. 10 is a perspective view of the plate for 55 the guide member; and

Fig. 11 is a perspective view of the guide member.

Referring more in detail to the drawings illustrating my invention, the numeral 20 generally designates a conventional steam boiler, or the like, having a lower annular base portion 21 adapted to hold the grate, firebox, and ash pit, and an upper portion 22 housing the water jacket 23. Below the level of the lower portion 21 is a wind box or air chamber. In the center of wind box 24 is an ash box 25 comprising a three-sided, metallic, rectangular box having a cover 26. The front open side of the box 25 is provided with an inclined passageway portion 27 leading to the bottom of the front of the furnace and closed by 15 a door 28.

Referring to Fig. 4, the cover 26 of the box 25 comprises an annular plate having a central opening 29 and surmounted by an annular ridge or flange portion 30. The ridge or flange 30 is centrally grooved as at 31 to form a bearing surface for receiving a plurality of conventional ball bearings 32. The cover 26 is also provided, in the opening 29, with four integral laterally extending tongues 33 equally spaced about the inner periphery of the opening 29.

Rotatably mounted on the bearings 32 in the groove 31 is a turn table 34 having an outer annular flange 35 with a depending portion surrounding the upturned flange 30. The flange 35 is provided with a bearing groove 36 adapted to ride over the top of the bearings 32. The turn table 34 comprises two vertically spaced inwardly extending flanges 37 and 38. The flange 37 extends to the inner edge of the opening 29 in the cover 26 and the flange 38 extends inwardly a lesser distance. A table plate 39 is keyed to the turn table 34 and is rotatable therewith. The table plate 39 is made up of a plurality of sections 40, see Fig. 3, having tapered side edges and 40 forming a central opening 41 above the central opening in the turn table and cover 26. Integrally formed with each section 40 of the plate 39 are vertically disposed ratchet teeth 42. The inner edge of each section 40 is provided with a 45 slot 43, each slot 43 registering with a slot 44 in the flange 38. The sections 40 are bolted together on the table plate 39 on each side of the slots 43, as shown in Fig. 3.

Radially disposed about the upper surface of 50 the plate 39 are a plurality of interlocking grate portions 45 disposed as in Figs. 1 and 3. Each grate portion 45 comprises an upper flat portion 46 provided with a plurality of air openings 47, and two spaced feet or flanges 48 (see Fig. 2), 55

providing an air space or passageway 49 beneath the upper portion 46. Referring to Fig. 2, each section 45 is provided with an integral laterally extending flange 50 on a side edge below the top 5 and an integrally laterally extending flange 51 on opposite side at the top so that when each complementary section 45 is placed next to a similar section the upper flange to the right will ride upon the lower flange to the left of the next section, thus interlocking the various sections. Each 10 of the segments 45 is bolted at its outer edge, to the table plate sections 40, as by means of bolts 52.

Extending around the upper outer surface of the grate portions 45 is a seal ring 53 made in a plurality of sections, each section having an extended prong 54 on one side adapted to slide into a cut-out portion 55 in the adjacent flange portion. The inner edge of the plate 39, surrounding the central opening 41, is surmounted by an 15 annular L-shaped casting 56 also made in a plurality of sections, each section provided at its inner edge with horizontally spaced slotted openings 57 providing air passageways. The under-side of each of the segments 56 is provided with 20 an integral depending lock tongue 58 extending through the slotted openings 43 and 44 and locking the plate sections 40 to the plate 39 and to the turn table 34.

The inner edge of the lower portion 21 of the 25 boiler 20 is provided with a plurality of angle irons 59 adapted to support a laterally extending annular plate 60 made in sections 61, such as those shown in Fig. 8. Each plate 61 is provided with a central depending flange 62 and an inner 30 depending flange 63 having spaced expansion slots 64. The flanges 62 and 63 are adapted to be positioned on the inner and outer peripheries respectively of the seal ring 53 as shown in Fig. 4. Referring to Fig. 8, the upper edge of each of 35 the sections 61 is provided with a plurality of evenly spaced angularly cut-out platforms 65. Mounted on the flange 61 is an inner flange 66, shown in Fig. 9, comprising an inner flange portion 67 having a plurality of spaced expansion 40 slots 68, and having laterally extending angularly cut-out tongues 69 adapted to interlock with the platforms 65 on the portion 61. An L-shaped fine brick may be used instead of the flange 66.

Near the front of the furnace, the top of the 45 stationary flange 61 is clear of the cut-out portions 65 and is overlapped by the inner edge of a plate 70 which curves inwardly to form an apex 71 extending towards the center of the grate. The plate 70 is slotted, as at 72, and is provided 50 with integral lock pins 73 on the under surface thereof. Mounted beneath the plate 70 is a flange 74, shown in Fig. 11, which has a depending wall 75 along the inner edge of the grate and extending towards the center thereof. The 55 depending wall 75 is slotted, as at 76, and has an upper integral plate portion 77 adapted to extend beneath the plate 70. The upper plate portion 77 is provided with an opening 78 to which it can be pinned to the plate 70 and interlocking slots 79 adapted to interlock with the pins 73 to permit a floating action.

The opening in the central portion of the grate 60 is provided with a drop cover 80 which is pivoted, as at 81, to a frame 82, set in the inner 65 periphery of the opening. The frame 82 comprises two segments having depending flanges 83 resting on the tongues 33 in the lower cover 26. The two segments are bolted together in the front and rear portions as at 84. Referring 70 to Fig. 4, a rod 85 is pivoted to the underside of

the cover 80 and extends through a slot 86 to the front of the furnace. The protruding end of the rod 85 may be provided with a suitable handle 87 and an intermediate portion thereof, adjacent the slot 86, may be provided with a shoulder 88. When the rod 85 is pulled outwardly by means of the handle 87, it will swing the cover 80 upwardly to close the opening, the shoulder 88 engaging the lower end of the slot 86 to hold it in place. 10

The above description completes the structure of the grate portion of the furnace of the present invention. As can readily be seen, the ash pit box 25, its cover 26, the frame 82, and cover 80 in the central portion are stationary. The turn 15 table 34, gears 42, plate 39, the segments 40, the grate members 45 and the seal rings 53, including the portion 56 surrounding the central opening, are all rotatable. The angle irons 59 supporting the plate 60 and angle irons 61, 66, and members 70 and 74 are also stationary. The internal fire-brick 89 is built upon the plate 60 and supported by the angle iron 59, as shown in Fig. 2. 20

The stoker mechanism comprises a hopper 90 communicating with a horizontal channel 91 which extends through the firebrick 89 through an opening 92 as shown in Figs. 1 and 2. Referring to Figs. 5 and 6, a ram 93 is slidable within the channel 91. The ram is actuated by a connecting link 94 which is in turn operated by means of the slidable sleeve 95, operated by a crank and motor movement not shown. The stroke of the link 94 may be regulated by means of the adjustable abutment collar 97 in the rear portion thereof; a stationary collar 98 is provided as an abutment for the sleeve 95. Depending from the ram 93 is an arm 100 to which is attached a horizontal bar 101 having a vertical plate 102. Extending from the lower end of the plate 102 are a pair of parallel bars 103 held in rigid position by means of angle irons 104. The bars 103, see Fig. 5, are journaled in a pair of bearings 105 for horizontal reciprocation. A plate 106 straddles the bars 103 between the bearings 105 and carries a pawl 107 which is adapted to engage the teeth 42 on the turn table. The pawl 107 may be spring pressed, as shown, or may be actuated by a counterweight. The slant of the teeth and the disposition of the pawl is such that forward movement of the pawl causes rotation of the turn table and grate in a clockwise direction. 35

The motor used to operate the ram heretofore described may also be used to operate the conventional blower 108 which communicates through 40 the passageway 109 with the lower portion of the surface surrounding the outside of the ash box 25, as shown in Fig. 7. 50

The operation of the apparatus can now be described as follows: The hopper 90 is filled with 45 coal. When the ram 93 is drawn back in a position shown in Fig. 6, the coal will enter the passageway 91 and the forward movement of the ram 93 will push the coal upon the grate 45 adjacent the outer periphery thereof corresponding 55 to the outer edge of the grate shown in Fig. 1. At the same time the rod 101 will push the plate 102 and the rods 103 so that the pawl 107 will engage the ratchet teeth 42 and turn the turn table, and the grate portions in a clockwise direction. 60 The ram now moves back, and the ram will again turn the turn table and deposit another portion of coal behind the first portion deposited. As the ram continues to operate and the turn table continues to turn, the coal, ignited by the 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

burning fuel previously placed in the furnace, will continue to rotate around upon the outer periphery of the grate until the inwardly extending portions 70 and 74 are reached. At this point, the partially burnt coal will be pushed towards the center of the grate and will continue around in another circle within the outer one. As more and more burning coal travels around upon the outside of the grate and is pushed towards the center by the portions 70 and 74, the previous portions are pushed further and further along towards the center of the grate, the timing being such that when the coal is approximately completely consumed and turned to ash, it will be pushed from the rotating inner portion 57 onto the closed door 80. Thus, the grate will be always entirely free of ash and will hold only burning fuel. When a sufficient quantity of ashes have accumulated on the drop door 80, it is merely necessary to lift the handle 81 and bar 85 and move it forwardly. This will swing the door 80 downwardly and allow the ashes to drop into the box 25 from whence they can be removed through the door 28. The door can then be swung back into closed position by hooking the shoulder 88 over the edge of the slot 86.

While this is going on, the grate is furnished with a proper draft from the blower 108 through the passageway 109 and into the wind box, but not into the ash box, so that the draft is confined to the outside of the ash box as shown in Fig. 7. As can readily be seen in Fig. 2, the draft flows upwardly and enters the passageway 49 beneath the grate portions 45, up through the openings 47 and through the various slots disposed about the inner periphery of the grate to form an upward current of air to burn the fuel entering from the outer side edge. This current of air is so disposed that it will not disturb or swirl any of the ashes nor can it be clogged by any ashes or accumulated waste material.

If desired, the inwardly extending plates 70 and 74 may be surmounted by an additional plate 110 pivoted at 111 and connected to the plate 102 which operates the ram, by a rod 112. With this connection, the portion 110 will be swung forwardly with each deposit of fresh coal upon the grate to give the partially burned coal an additional push towards the center of the grate.

While the drawings and description show a ram stoker and ratchet and pawl drive, it is possible to use a screw in the passageway 91 for continuously pushing a quantity of coal upon the grate. Instead of the pawl and ratchet arrangement a worm drive may also be used on the grate at the same time for causing a continuous movement of the grate to conform with the continuous deposit of coal by means of the screw.

Although the grate is shown as round, it is obvious that the boiler can be in any desired shape and the corner portions thereof, not conforming to the circular grate, may be filled in with any suitable material such as firebrick and the like.

It is obvious from the foregoing that the stoker and grate arrangement of the present invention are easy and economical to manufacture and assemble and are admirably adapted for the intended purpose. In view of the intense heat at the point of fuel consumption in similar types of grates, it is often very difficult to replace burnt-out and cracked parts. By utilizing the construction of the present invention, it is very simple to replace particular broken sections without disturbing the entire arrangement. Furthermore, the parts are so interlocked that there is

little or no seepage of air causing cross drafts where it is not wanted or required. By utilizing the construction of the present invention, the ash pit is free of any draft and the draft is directed to the proper place directly beneath the burning fuel by means of special channels beneath each particular grate segment.

While I have described a specific constructional embodiment of my invention, it is obvious that any change in size and shape of the various parts and in their arrangement may be made to suit the requirement for different installations without departing from the spirit and the scope of the present invention, as defined in the appended claims.

I claim:

1. In a mechanical stoker, an annular rotatable grate, said grate comprising a plurality of sections having draft flow passageways extending laterally beneath the upper surface of said grate and communicating therewith, a fuel hopper, means for positively feeding measured quantities of fuel from said hopper tangentially to the outer edge of said grate, and for rotating said grate in timed relation to the positive feed of the fuel, and means positioned at the outer edge of the grate and adjustably movable inwardly for guiding the burning fuel in concentric circles on said grate progressively toward the center of said grate.

2. In a mechanical stoker, an annular rotatable grate, a fuel hopper, an ash box beneath said grate communicating with the central portion of said grate, means for positively feeding measured quantities of fuel from said hopper tangentially to the outer edge of said grate, and for rotating said grate in timed relation to the positive feed of the fuel and means positioned at the outer edge of the grate and adjustably movable inwardly for guiding the burning fuel in concentric circles on said grate progressively toward the center of said grate.

3. In a mechanical stoker, an annular rotatable grate, a fuel hopper, means for positively feeding measured quantities of fuel from said hopper tangentially to the outer edge of said grate, and for rotating said grate in timed relation to the positive feed of the fuel, and means positioned at the outer edge of the grate and adjustably movable inwardly for guiding the burning fuel in concentric circles on said grate progressively toward the center of said grate, said feeding means including a motor-driven ram reciprocatable in a passageway between said hopper and the upper surface of said grate.

4. In a mechanical stoker, an annular rotatable grate, said grate comprising a plurality of sections having draft flow passageways extending laterally beneath the upper surface of said grate and communicating therewith, a fuel hopper, means for positively feeding measured quantities of fuel from said hopper tangentially to the outer edge of said grate, and for rotating said grate in timed relation to the positive feed of the fuel, means positioned at the outer edge of the grate and adjustably movable inwardly for guiding the burning fuel in concentric circles on said grate progressively toward the center of said grate, and a blower for forcing a draft through said draft flow passageways.

5. In a mechanical stoker, an annular rotatable grate, a fuel hopper, an ash box beneath said grate communicating with the central portion of said grate, means for positively feeding measured quantities of fuel from said hopper tangentially to the outer edge of said grate, and for

rotating said grate in timed relation to the positive feed of the fuel, means positioned at the outer edge of the grate and adjustably movable inwardly for guiding the burning fuel in concentric circles progressively toward the center of said grate, and a blower for forcing a draft beneath the burning fuel on said grate.

6. In a mechanical stoker, an annular rotatable grate, said grate comprising a plurality of sections having draft flow passageways extending laterally beneath the upper surface of said

grate and communicating therewith, a fuel hopper, means for positively feeding measured quantities of fuel from said hopper tangentially to the outer edge of said grate, and for rotating said grate in timed relation to the positive feed of the fuel, and means positioned at the outer edge of the grate and adjustably movable inwardly for guiding the burning fuel in concentric circles on said grate progressively toward the center of said grate.

MILBURN E. YEAGER.
